Primary Examiner — Marie D. Fast Horse(74) *Attorney, Agent, or Firm* — Tucker Ellis LLP(57) **CLAIM**

The ornamental design for an entry phone, as shown and described.

DESCRIPTION

FIG. 1 is a front, right and top perspective view of an entry phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The claim is directed to the design shown in solid lines, while the surfaces shown between the solid lines and the broken lines form no part of the claimed design.

1 Claim, 4 Drawing Sheets(56)
